FIG. 1.

To all whom it may concern:

Be it known that we, Lewis C. Schaeffer and Harry Lemmons, both citizens of the United States, residing at Fremont and Dallas, in the counties of Steuben and Dallas respectively, and States of Indiana and Texas, have invented a new, original, and ornamental Design for a Combination Food Slicer and Cutter, of which the following is a specification, reference being had to the accompanying drawing, forming part thereof.

In the drawing,

Fig. 1 is a side elevational view of a combination food slicer and cutter embodying our new design,

Fig. 2 is a front elevational view, and

Fig. 3 is a top plan view.

The essential features of our design reside in the portions shown in full lines.

We claim:

The ornamental design for a combination food slicer and cutter, substantially as shown and described.
